UNITED STATES PATENT OFFICE

WILLIAM CARTER, OF ISLINGTON, LONDON, ENGLAND

SIGN

Application filed April 25, 1930, Serial No. 447,805, and in Great Britain June 18, 1929.

This invention relates to advertising and like signs of the so-called "reflex" type in which stencils are arranged above an inclined reflecting surface so that light passing downwards through the stencil is directed through the front of the sign to the eye of the observer, or in which light passing downwards onto an inclined light-reflecting or refracting surface is thereby diverted through a stencil 5 arranged at the front of the sign.

The invention has for its principal object to provide an improved, simple and effective construction of sign of the aforesaid type, more particularly for use on motor vehicles, 15 whereby colour-changing or flickering effects may be secured in an economical manner by the swaying or other motion of the vehicle.

The invention is hereinafter described by way of example with reference to the accompanying diagrammatic drawings, in which:—

Figure 1 is a sectional side elevation illustrating the application of the invention to a sign of the type first referred to;

Figure 2 is a top plan view corresponding 25 to Figure 1 with part of the upper stencil removed; and

Figure 3 is a view similar to Figure 1 illustrating the application of the invention to the second-mentioned type of sign.

30 In carrying the invention into effect according to one construction and with reference to Figures 1 and 2 of the accompanying diagrammatic drawings, the upper part of the casing 1 of a sign having an inclined rear wall 2 carrying a reflector 3 by which the sign is displayed through an aperture 4 in the front wall 5 of the casing, is modified for the reception of upper and lower duplicated stencils 6, 7 spaced apart or arranged for the slide- 35 able reception of a member constituted by two sheets 8, 9 of glass or the like enclosing between them a transparency 10 or transparencies, such sliding member, as shown in Figure 2, being of shorter length than the stencils 40 to allow for the required movement of the member to and fro. The glass sheets are held together by adhesive and the transparencies or colored plates will be firmly held by and between them so that the color plates 45 need not be coextensive with the glass sheets

provided they have a sufficient area to cover the respectively associated opening of the stencil in all positions of the slide. The stencils 6, 7 are provided at their inner sides with strips or pieces 11, 11a respectively, of felt or like material between which the composite member 8, 9, 10 slides freely, such strips or pieces of felt 11, 11a being disposed, as shown in Figure 2, adjacent to the edges of the juxtaposed apertures 6a, 7a of the stencils 6, 7 so as to keep the portions of the glass 55 8, 9 which co-operate with the apertures 6a, 7a clean. The stencils preferably are of substantially the same length as the casing so as to be held against movement by the end walls 60 of the casing but they may be held stationary in any preferred or convenient manner.

As shown more particularly in Figure 2, each transparency 10a, associated for example with the main lettering and devices of the advertisement or the like, may be of a single colour so that during the movement of the slideable composite member 8, 9, 10 to the limits determined by spring stops or rubber buffers 12 at the ends of the sign casing, the colour of such parts of the stencil does not change. On the other hand, certain parts of the stencil, such as the aperture 6b, may have associated therewith transparencies 75 10b, 10c arranged so that in the movement of the composite member 8, 9, 10 the colour of such parts changes. With the arrangement according to the invention it is also possible to secure an effective endwise oscillating or moving wavy underline or border. Thus, in 80 the example shown, a longitudinal slot 13 of wavy formation is cut in the respective stencils 6, 7 and each end of the transparency 10d, which may be constituted by alternating 85 sections of different colour, terminates in an opaque portion 10e so that the overall length of the transparency 10d is somewhat less than the length of the wavy slot 13 with the result that on movement of the composite member 90 8, 9, 10 the wavy underline appears to run along or to oscillate endwise.

In the application of the invention to a sign of the second-mentioned type, as shown in Figure 3, the duplicate stencils 6, 7 and the composite member 8, 9, 10 slideable between 95 100

the strips 11, 11a of felt or like material, are arranged vertically behind the aperture 4 in the front wall 5 of the sign casing, the stencils being supported, for example, in a shallow trough-like formation 17 at the bottom of the casing and at the top by means of a suitable flanged member 18.

When the sign is mounted upon a vehicle, preferably transversely, the swaying, oscillatory or other motion of the vehicle when running is sufficient to cause the movement of the slideable member to give the colour-changing or flickering effects. If desired, however, the movement of the slideable member may be effected mechanically, for instance by the opening and closing of a door.

It will be understood that the invention is not limited to the particular details of construction hereinbefore described. Thus, for example, in the construction of Figure 1, the strips or pieces 11 of felt or the like fixed to the underside of the upper stencil 6 may be dispensed with, while the arrangement of the apertured portions of the stencil and of the transparencies co-operating therewith obviously may be modified in various ways to secure any desired effects.

What I claim is:—

1. An advertising sign comprising a casing having two open sides at an angle to each other, a reflector in the casing at an angle to the open sides thereof whereby to reflect through one side, a pair of duplicate stencils set in the other open side of the casing, a transparent slide fitted between the stencils for limited reciprocation, and color plates on the slide located to cover the respective openings in the stencils in all positions of the slide, said plates being of various colors.

2. An advertising sign comprising a casing having two open sides at an angle to each other, a reflector in the casing at an angle to the open sides thereof whereby to reflect through one side, a pair of duplicate stencils set in the other open side of the casing, and a slide fitted between the stencils and consisting of two sheets of glass secured together and color plates between the glass sheets, the color plates being of various colors and arranged to cover the openings in the stencils in all positions whereby to color the light passing through said openings to the reflector.

3. An advertising sign comprising a casing having two open sides at an angle to each other, a reflector in the casing at an angle to the open sides thereof whereby to reflect through one side, a pair of duplicate stencils set in the other open side of the casing, a transparent slide fitted between the stencils for limited reciprocation, color plates on the slide located to cover the respective openings in the stencils in all positions of the slide, said plates being of various colors, and strips of cushioning and cleaning material fixed on

the inner face of a stencil adjacent the respective openings therein.

4. An advertising sign comprising a casing having two open sides at an angle to each other, a reflector in the casing at an angle to the open sides thereof whereby to reflect through one side, a pair of duplicate stencils set in the other open side of the casing, a transparent slide fitted between the stencils for limited reciprocation, color plates on the slide located to cover the respective openings in the stencils in all positions of the slide, said plates being of various colors, and buffers at the ends of the casing to arrest the movement of the slide.

5. An advertising sign comprising a casing having two open sides at an angle to each other, a reflector in the casing at an angle to the open sides thereof whereby to reflect through one side, a pair of duplicate stencils set in the other open side of the casing, a transparent slide fitted between the stencils for limited reciprocation, and color plates on the slide located to cover the respective openings in the stencils in all positions of the slide, the color plates being of various colors.

6. An advertising sign comprising a casing having two open sides at an angle to each other, a reflector in the casing at an angle to the open sides thereof whereby to reflect through one side, a pair of duplicate stencils set in the other open side of the casing, a transparent slide fitted between the stencils for limited reciprocation, color plates on the slide located to cover the respective openings in the stencils in all positions of the slide, the stencil plates having a border opening of undulatory formation, and a color plate fixed on the slide to register with said undulatory opening and of less length than said opening.

WILLIAM CARTER.
